UNITED STATES PATENT OFFICE.

CHARLES A. WOOLSEY AND HENRY V. BOWMAN, OF MINNEAPOLIS, MINNESOTA, AS-SIGNORS TO NORTHWESTERN COLLAPSIBLE CARRIER CO., OF ST. PAUL, MINNESOTA, A CORPORATION OF MINNESOTA.

CRATE.

Application filed April 14, 1924. Serial No. 706,314.

The object of our present invention is to provide improved means for supporting the bottom of a crate to the end that it can be easily and quickly assembled and secured to the crate walls. 55

A further object is to provide a crate bottom which will be extremely strong and durable in construction and capable of withstanding a rough usage to which a crate is frequently subjected. 60

The invention consists generally in various constructions and combinations all as hereinafter described and particularly pointed out in the claims. 65

15 In the accompanying drawings forming part of this specification,

Figure 1 is a perspective view of a crate embodying my invention;

Figure 2 is a similar view of the crate bottom removed from the crate; 70

Figure 3 is a detail sectional view of the crate bottom shown in Figure 2 illustrating the manner of securing it to the walls of the crate; 75

25 Figure 4 is a sectional view on the line 4-4 of Figure 3;

Figure 5 is a sectional view on the line 5-5 of Figure 3;

Figure 6 is a plan view of a crate bottom 80 showing a modified construction;

Figure 7 is a sectional view on the line 7-7 of Figure 6;

Figure 8 is a sectional view of a modified form of the invention, taken on the line 8-8 of Figure 9;

Figure 9 is a sectional view on the line 9-9 of Figure 8;

Figure 10 is a detail sectional view showing a modified means for supporting the 49 bottom in the crate. Figs. 11 and 12 are details of a modified construction.

In the drawing, 2 represents the side walls of the crate and 3 the end walls secured together at the corner by angle plates 4 45 and having at the bottom the reinforcing and bracing corner irons 5 which extend up on the outside of the crate corners and on the inside has ears 6 and 7 secured respectively to the end and side walls of the 50 crate. These walls as indicated are preferably composed of a series of narrow slats placed edge to edge and held by the corner plates and as indicated in Figure 1 the side and end walls preferably have ventilating

gaps 8 formed by removing the middle portions of one of the slats in each wall. This, however, forms a portion of the subject-matter of Patent Number 1,594,029, granted July 27, 1926, and we therefore make no claim to the same herein, this application 60 being drawn particularly to the improved bottom for the crate and the means for securing it to the walls.

In Figure 2, we have illustrated one style of bottom comprising channel bars 9 65 adapted to receive the ends of the slats 10 and 11 composing the bottom of the crate. The bars 9 are preferably formed from sheet metal of suitable gage, preferably galvanized, and the slats are spaced apart in 70 these bars and one of the flanges of the channel has ears 12 pressed therefrom and turned down into the gaps between the bars for the purpose of holding them in position. The slats may have a slight lateral 75 movement but any considerable lateral motion will be prevented by the ears. The outer slats as shown plainly in Figure 3 are preferably of thicker material than those in the middle to form runners or shoes on 80 which the crate may be pushed from point to point on the floor, the under surface of these slats preferably depending below the side and end walls and forming the only contact of the crate with the floor. The 85 ends of the bars 9 have upwardly turned ears 13 which fit against end walls of the crate and are secured thereto by rivets 14 which pass through the ears and through 90 the wall of the crate and the reinforcing corner irons. When these rivets are cut or removed, the bottom can be readily separated from the crate walls.

In Figures 6 and 7, we have shown a modified construction which consists in 95 omitting the ears 12 and placing the slats in the bars in contacting relation to make a solid bottom and securing the outer slats in the bars by suitable means such as rivets 15. The ears 13 at the ends of the bars correspond to those shown in Figure 1 and we will designate them by the same reference numeral with the addition of the exponent "a" and we will indicate the bar itself in Figures 6 and 7 by numeral 9^a. The outer slat 100 in Figure 6 is made thicker than the others for the same purpose as described with reference to the previous figures. 105

In Figures 8 and 9, we have shown another modification which consists in providing a channel bar 9^b and forming longitudinal slots 16 in the ends thereof to receive the ears 6 of the corner irons, the bars and irons being assembled and then placed in position in the crate and secured by rivets 14^a passing through the walls of the box and the inner and outer portions of the corner irons. Evidently, as shown in Figures 8 and 9, these irons will sustain the load of the bottom of the crate and when the parts are assembled and secured in the crate, it will be impossible for the bottom to become separated.

In Figure 10, we have shown a channel bar 9^c having the bottom slats mounted therein in the manner described with reference to Figure 7 but the supporting ears 13^c instead of being formed to fit the end wall of the crate and secured thereto are folded to bear on the side walls and are supported by the same rivets that secure the ears 7 of the corner irons to the side walls. In other respects, the bottom is substantially the same as described with reference to the previous figures. Evidently with this construction, the bottom of the crate will be firmly held and capable of withstanding any load to which the crate may be subjected. At the same time, whenever desired, the supporting rivets may be cut and the bottom easily and quickly removed for substitution or repairs.

In Figure 11, we have shown a modified construction which consists in providing an angle bar having a vertical flange 17 to fit against the end wall of the container or crate and secured thereto by rivets 14^a corresponding to those for a similar purpose illustrated in Figure 3. The horizontal flange 18 of the angle bar supports the floor slats 10 and 11 and these slats are secured to the angle by rivets 19.

In Figure 12, we have shown a modified

means for securing the floor which consists in a plate 20 bridging the ends of the bottom slats and secured to the slats 10 by a rivet 19^a. Evidently, when the supporting rivets are severed, the angles and the bottom may be easily and quickly removed from the container or crate.

We claim as our invention:

1. A crate comprising side and end walls and reinforcing means at the corners for securing said walls together, corner irons fitting the lower corners of the crate and secured to the adjacent side and end walls, bars fitting said end walls on the inside of the crate, and having ears secured to said end walls through said reinforcing means and said corner irons, and a bottom having its ends inserted into said bars and supported and secured thereby.

2. A container comprising side and end walls, angle plates for reinforcing said side and end walls at the corners, corner irons provided at the bottom of said container and having ears extending upwardly on the inner and outer side of the corners, bars seated against said end walls and having horizontal flanges, and a bottom for said container seated on said flanges, said bars having upright flanges and rivets passing through said upright flanges and through the ears of said corner irons and securing said bars and walls together.

3. A container comprising side and end walls connected by corner brackets, bars fitting against the brackets on the inside of the container, a bottom having ends fitting said bars and supported thereby, said bars having ears fitting against the bracket, and rivets passing through the ears, brackets and walls.

In witness whereof, we have hereunto set our hands this 3rd day of April 1924.

CHARLES A. WOOLSEY.
HENRY V. BOWMAN,
